UNITED STATES PATENT OFFICE.

JOHN CLYDE, OF MARION CENTER, AND MILTON STUCHELL, OF BIG RUN, PENNSYLVANIA.

CHECKREIN-HOLDER.

SPECIFICATION forming part of Letters Patent No. 657,915, dated September 18, 1900.

Application filed June 13, 1900. Serial No. 20,208. (No model.)

To all whom it may concern:

Be it known that we, JOHN CLYDE, residing at Marion Center, in the county of Indiana, and MILTON STUCHELL, residing at 5 Big Run, in the county of Jefferson, State of Pennsylvania, citizens of the United States, have invented certain new and useful Improvements in Checkrein-Holders; and we do hereby declare the following to be a full, clear, 10 and exact description of the invention, such as will enable others skilled in the art to which it appertains to make and use the same.

This invention relates to harness, and more especially to the checkreins used therein; and 15 the object of the same is to produce an improved checkrein-holder.

To this end the invention consists in the peculiar construction of parts, as hereinafter more fully described and claimed, and as illustrated in the accompanying drawings, where- 20 in—

Figure 1 is a perspective view of this device entire, with the checkrein pulled to the rear of the casing. Fig. 2 is a central longitudinal section showing the tongue as engaged with the notch within the casing, so that the horse is checked. Fig. 3 is a cross-section through the device with the tongue housed between the lips and the strap and 25 plate lying within the groove. Fig. 4 is a perspective detail of the tongue and its supporting-plate and a portion of the checkrein inverted.

In the accompanying drawings, 1 designates the harness-saddle, upon whose arch is 35 supported a casing, consisting of a base 2, having a longitudinal groove 3 in its upper face, which groove is provided with a rearwardly-facing notch 4, and over this base extends a frame-plate 5, secured to the sides of the base, while the latter is secured upon the saddle in any preferred way. However, the entire casing may be constructed in any other suitable manner so long as it has the longitudinal groove with the notch in its bottom. 40

10 designates the check-strap, having a snap-hook 11 at its front end, to which is attached the checkrein, as will be clearly understood, while the rear end of the strap extends 45 back to within reach of the driver.

Upon this strap is riveted a plate 12, having depending parallel lips 13, which extend downward through a slot in the strap, as seen in Fig. 4, and between which is pivoted a tongue 15 in such manner and of such length 55 that it may be swung in either direction and of such size that when swung to either horizontal position it will be housed within the thickness of the plate and lips.

In use the checkrein is attached to the snap-hook and the strap passed through the longitudinal opening in the casing. When it is desired to check the horse, the strap 10 is drawn to the rear until the plate, and with it the tongue, passes into the casing. When the 60 operator can just see the rear extremity of the plate, he releases his pull and the strap, plate, and tongue move forward until the latter engages the notch within the groove and the horse is checked. To uncheck, the strap 65 10 is drawn to the rear until the plate and tongue come out of the casing and the release of the tension on the strap then permits the tongue to pass through the casing while housed between the lips in the other direction, 70 whereby it will not engage the notch. In other words, the tongue moves freely through the casing in either direction whenever its pivot moves in advance of its tip and little practice is necessary to enable the operator to check and uncheck the horse while 75 sitting in the vehicle.

The parts are of the desired sizes, shapes, proportions, and materials.

What is claimed as new is—

1. In a checkrein-holder, the combination with the check-strap having a slot, and a tongue pivoted at one end within said slot midway of the length of the latter and adapted to be swung into diametrically-opposite positions and housed therein; of a casing mounted on the harness-saddle and provided with a longitudinal groove for the strap and a transverse notch for the tongue, substantially as described. 95

2. In a checkrein-holder, the combination with the check-strap having a slot, a plate secured thereover and having longitudinal lips standing within the slot, and a tongue pivoted at one end between said lips and adapt- 100

ed to be swung in either direction and housed between the lips and within the slot; of a casing mounted on the harness-saddle and provided with a longitudinal groove for the strap and a transverse notch for the tongue, substantially as described.

3. In a checkrein-holder, the combination with the check-strap having a slot, and a tongue pivoted at one end within said slot and adapted to be swung in either direction and housed therein; of a casing consisting of a base mounted on the harness-saddle and provided with a longitudinal groove adapted

to freely receive the strap and a transverse notch adapted to engage the tip of the tongue, and a frame-plate secured upon the base and extending over the top of the groove, substantially as described. 15

In testimony whereof we affix our signatures in presence of two witnesses.

JOHN CLYDE.
MILTON STUCHELL.
